UNITED STATES PATENT OFFICE.

RICHARD S. HARVEY, OF WASHINGTON, DISTRICT OF COLUMBIA.

PROJECTILE.

1,312,114.

Specification of Letters Patent.

Patented Aug. 5, 1919.

Application filed May 21, 1917. Serial No. 170,040.

To all whom it may concern:

Be it known that I, RICHARD S. HARVEY, a citizen of the United States, residing at Washington, District of Columbia, have invented and discovered certain new and useful Improvements in Projectiles, of which the following is a specification.

My said invention relates to bombs, or projectiles of the explosive type, and consists in the combinations and arrangements of elements hereinafter described and particularly set forth in the accompanying claims.

The invention has for its purpose to provide a projectile, or bomb, adapted for destroying or disabling submarines when submerged, and which may be fired from the air, from ships, or from the shore, with accuracy and by the types of guns now in use.

A further purpose of the invention is to produce a submersible bomb, or projectile, adapted to penetrate the water for a given depth and then be exploded by an element offering resistance to the water; and having means for predetermining the depth of submergence before exploding, in accordance with the distance from the surface of the object to be fired at.

The invention is disclosed by way of illustration in the accompanying drawings, wherein—

Fig. 1 is a side elevational view of the projectile,

Fig. 2 a central longitudinal sectional view thereof,

Fig. 3 an elevational view of the base of the shell (on the line 3—3 of Fig. 2),

Fig. 4 a transverse sectional view on the line 4—4 of Fig. 2,

Fig. 5 a transverse sectional view on the line 5—5 of Fig. 2,

Fig. 6 a detail sectional view of a part of the resistance element release, and the percussion or ignition device,

Fig. 7 an end elevational view of the projectile, showing the resistant device in position of operation,

Fig. 8 a side elevational view showing the same,

Fig. 9 a side elevational view showing the manner of separation of the projectile parts in the water, and

Fig. 10 illustrates the projectile provided with a device to prevent ricochetting.

Referring to the construction in further detail and with like reference characters designating corresponding parts in the dif-

ferent views shown, the projectile consists of an explosive shell having an outer casing 1, an inner casing 2 and a base piece 3, containing the explosive charge 4 after the usual manner. A separate casing 5 forms part of the explosive shell and carries a plurality of blades 6 pivotally mounted as at 7 and adapted to be moved radially through the resistance of the water after the manner indicated in Figs. 7, 8 and 9, and which movement operates to release the explosive shell to allow the latter to continue its submerged course for a predetermined distance.

Each of the blades 7 is provided with a pin 8 adapted to enter apertures 9 formed in the periphery of the base piece 3 and thereby hold the separable portion to the explosive shell for that portion of the trajectory that is through the air and immediately entering the water. The several blades 6 forming the resistant element of the device are normally held in inoperative position by means of a ring 10 contained and slidably mounted within the shell 5 and engaging the extended end portions 11 of the blades as shown (see Fig. 2).

The locking ring 10 is mounted on a spider 12 which engages at its central portion 13 with the upper end of a plunger 14 that is formed with a stem portion 15 working in a sleeve or bearing 16, and extending through the central longitudinal axis of the projectile and projecting through nose 17 thereof. A disk 18 is mounted on the outer end of the plunger rod 15 and adapted to impact with the water to axially displace the locking ring 10 and release the several blades 6 to be readily projected. The initial radial movement of said blades is effected by means of a spring 19 for each blade (see Figs. 2 and 4). Each spring 19 is anchored to a pin or screw 20 secured to the shell 5, and at its opposite end connects with a lug 21 on the inner side of the blade projection 11.

The projectile is provided with means for accelerating or initially imparting the separation of the shell proper and the casing 1, and said means consists of a spring 22 located within the recess 23 formed in the base 3 of the shell. Said spring is held under high tension between the shell and the removable portion and expands, on the release of the locked blades, to separate these elements with acceleration, as will be understood.

The locking ring 10 is normally held to hold the blades by means of a number of springs 24 that connect with the spider arms 12 and are anchored to the shell 5 as shown.

- 5 It will therefore be seen from the foregoing that immediately the shell strikes the water, the several blades 6 are released and spread into the position shown (see Fig. 7, 8 and 9), thus retarding this portion of the 10 projectile and allowing the body or explosive portion thereof to continue its travel, and through this retardation of the separate shell portion is effected the ignition and explosion of the charge 4; *i. e.*, when the explosive shell has reached the approximate 15 depth of submergence of the submarine or other object fired at.

The means for causing the ignition of the powder charge 4 consists of a percussion device 20 comprising caps or primers 25 and a striker or hammer 26, adapted to be impelled by the spring 27 (see Fig. 2). The striker and spring (26 and 27) are mounted within a tube 28 secured to the tubular piece 16 and 25 the plunger 14 works freely through said striker device to release the blades without interference with said striker.

The striker or hammer 26 is normally held under tension of the spring by a pin 29 30 mounted in the tube 14 and said pin is constructed preferably of a soft copper wire of sufficient strength to stay fixed on the operation of the plunger 15 to release the blades, but to give or break and allow the hammer 35 to strike the primer 25 at the proper instant.

The device for removing the stop pin 29 to release the hammer 26 consists of a thin cable or strand 30, *e. g.*, wire cord or the like, that carries an apertured piece 31 receiving 40 said pin 29 at one end, and which is wound on a reel 32 journaled in a stable bracket 33 mounted within the shell casing 5. A water-tight packing 34 is fitted in the upper end of the tube 14 for the purpose of preventing 45 water that may enter the casing 5 from gaining access into the powder chamber of the explosive shell.

It is proposed to predetermine the length of cord 30 to be let out in accordance with 50 the depth at which the shell is to be exploded, and this of course is approximated from the evident depth of submergence of the submarine or object to be fired at.

The adjustment device consists of a disk 55 35 fitting in a recess 36 in the base piece 37 of the projectile and mounted on a stud 38 journaled in said base piece, as shown. A crown pinion or gear 39 is secured to the lower end of the stud 38 and meshes with a 60 pinion 40, in turn meshing with a pinion 41 secured to the shaft carrying the reel 32. A plurality of apertures 42 are formed in the base piece 37 and adapted to receive a stop pin 43 to engage with a projection 44 of the 65 disk 35, and stop said disk from turning.

The stoppage of the disk will in turn stop the unwinding of the cable or chain 30, and this in turn will suddenly withdraw the pin 29 and allow the hammer 26 to strike the primer 25 and thereby ignite the charge. 70

The apertures 42 in the face of the base 37 are designated with characters determining the depth in feet or fathoms at which it is desired to lengthen the cable 30 and thereby explode the charge. It will therefore 75 be seen that by inserting the pin 43 into the desired aperture, that the explosion of the charge may in this manner be determined in accordance with the depth desired.

The projectile is adapted to be fired into 80 the water from aboard ship or off shore, but it is believed to be particularly adapted for firing or releasing from an aeroplane, and to this end it is proposed to provide a device for keeping straight the trajectory of 85 the projectile and to prevent ricochetting thereof, as will be understood. The device employed for this purpose consists of a staff 45 having vanes or blades 46 and adapted for engagement with the base piece 37 of the 90 projectile by the gripping arms 47, as shown. Said arms are designed to engage in an annular groove 48 formed in the periphery of the base piece 37, and a slip ring 49 slides on the split portion 50 of the staff 95 45 carrying the gripping arms 47. With this arrangement it will be obvious that the device may be readily applied to or removed from the projectile as desired.

Having thus fully described my said invention, what I claim as new and desire to secure by Letters Patent, is:

1. In a projectile or bomb designed to be submerged, the combination of an explosive shell having a separable portion, a flexible 105 connection between said separable portion and the shell operable to cause ignition of the explosive shell charge, and a device carried by said separable portion operable through water resistance to separate the same from 110 the shell, substantially as set forth.

2. In a projectile or bomb designed to be submerged, the combination of an explosive shell having a separable base portion, a flexible connection between said base portion and the shell operable to cause ignition of the explosive shell charge, a device carried by said base portion operable through water resistance to separate the same from the shell, and adjustable means carried by said base portion 115 120 for fixing the operating length of said flexible connection to explode the shell charge, substantially as set forth.

3. In a projectile or bomb designed to be submerged, the combination of an explosive shell having a separable portion, means carried by the separable portion operable through water resistance to separate said portion from the shell, means operable on water impact to release said separating 125 130

means, a flexible connection between said separable portion and the shell operable to cause ignition of the explosive shell charge, and adjustable means for fixing the operating length of said flexible connection to explode the shell charge, substantially as set forth.

4. In a projectile or bomb designed to be submerged, the combination of an explosive shell having a separable portion, blades carried by the separable portion operable through water resistance to separate said portion from the shell, a plunger operable on the water impact to release said blades to work, a flexible connection between said separable portion and the shell operable to cause ignition of the explosive shell charge, and an adjustable device mounted on the base of the projectile for fixing the operating length of said flexible connection to explode the shell charge, substantially as set forth.

5. In a projectile or bomb designed to be submerged, the combination of an explosive shell having a separable portion, a plurality of pivotally mounted blades carried by the separable portion operable through water resistance to separate said portion from the shell, a plunger passing through the central longitudinal axis of the projectile operable on impact to release said blades to work, a flexible connection between said separable portion and the shell operable to cause ignition of the explosive shell charge, and an adjustable device mounted on the base of the projectile for fixing the operating length of said flexible connection to explode the shell charge, substantially as set forth.

6. In a projectile or bomb designed to be submerged, the combination of an explosive shell having a separable portion, blades carried by the separable portion operable through water resistance to separate said portion from the shell, a plunger operable on water impact to release said blades to work, a reel carried by the separable portion, a flexible member wound on said reel and connected to the shell operable to cause ignition of the explosive shell charge, and an adjustable device mounted on the base of the projectile coöperable with the reel for fixing the operating length of said flexible connection to explode the shell charge, substantially as set forth.

7. In a projectile or bomb designed to be submerged, the combination of an explosive shell having a separable portion, blades carried by the separable portion operable through water resistance to separate said portion from the shell, a plunger operable on water impact to release said blades to work, a percussion device carried by the shell to ignite the shell charge, a flexible member carried by the separable portion and connected to said percussion device to actuate the same

for igniting the explosive charge, and an adjustable device mounted on the base of the projectile coöperable with the flexible member for fixing the operating length of said flexible connection to explode the shell 70 charge, substantially as set forth.

8. In a projectile or bomb designed to be submerged, the combination of an explosive shell having a separable portion, blades carried by the separable portion operable 75 through water resistance to separate said portion from the shell, a device for holding said blades in inactive position, a percussion device for igniting the combustible charge, means operable on water impact to release 80 said blade holding device, and means connecting said separable portion with the explosive shell operable to cause action of the percussion device to explode the shell, substantially as set forth.

9. In a projectile or bomb designed to be submerged, the combination of an explosive shell having a separable portion, a plurality of pivotally mounted blades carried by the separable portion operable through 90 water resistance to separate said portion from the shell, a device for holding said blades in inactive position, a device operable on water impact to release said blade holding device, a flexible connection between 95 said separable portion and the shell operable to cause ignition of the explosive shell charge, and an adjustable device mounted on the base of the projectile for fixing the operating length of said flexible connection 100 to explode the shell charge, substantially as set forth.

10. In a projectile or bomb, designed to be submerged, the combination of an explosive shell having a separable portion, a plurality 105 of pivotally mounted blades carried by the separable portion operable through water resistance to separate said portion from the shell, a device for holding said blades in inactive position, a percussion device, a flexible connection between said separable portion and the percussion device to cause ignition of the explosive shell charge, a lock 110 for the percussion device, and means operable on water impact to release said blade holding means, and means also operable through water impact to release the percussion lock, substantially as set forth.

11. In a projectile or bomb designed to be submerged, the combination of an explosive shell having a separable portion, a plurality of radially movable blades pivotally mounted on the separable portion and operable through water resistance to separate said portion from the shell, devices for 120 initially moving said blades into operative position, a locking member normally holding said blades in inoperative position, a plunger connected to said locking device 125 operable on water impact to release the lock 130

4

and free the blades, a percussion device for igniting the explosive shell charge, a lock for the percussion device mounted on said plunger, a flexible connection between said 5 separable portion and the percussion locking device to release the latter, and means carried by the separable portion for fixing the operating length of said flexible connection to release the percussion lock to explode the 10 shell charge at a predetermined period, substantially as set forth.

12. In a projectile or bomb designed to be submerged, the combination of an explosive shell having a separable portion, means carried by the separable portion operable 15 through water resistance to separate said portion from the shell, means operable on water impact to release said separating

means, a reel carried by the separable portion, a flexible member wound on said reel and connected to the shell operable to cause ignition of the explosive shell, a gearing connected to be operated by said reel, and selective means associated with said gearing for fixing the operating length of said flexible connection to explode the shell charge substantially as set forth.

In witness whereof, I have hereunto set my hand and seal at Washington, District of Columbia, this 19th day of May, A. D. nineteen hundred and seventeen.

RICHARD S. HARVEY. [L. S.]

Witnesses:

MARK F. FINLEY,
LESLIE STEAD.
